UNITED STATES PATENT OFFICE.

WILLIAM HORN, OF GLENSIDE, PENNSYLVANIA, ASSIGNOR TO HORN & BRANNEN
MANUFACTURING COMPANY, A CORPORATION OF PENNSYLVANIA.

DESIGN FOR A CHANDELIER CHAIN SUPPORT.

49,925.

Specification for Design.

Patented Nov. 21, 1916.

Application filed July 13, 1916. Serial No. 109,179. Term of patent 3½ years.

To all whom it may concern:

Be it known that I, WILLIAM HORN, a citizen of the United States, residing at Glenside, Montgomery county, State of Pennsylvania, have invented a certain new, original, and ornamental Design for a Chandelier Chain Support, of which the following is a specification, reference being had to the accompanying drawing, forming part thereof.

Figure 1 is a plan view of a chandelier

chain support, showing my new design; the ornamentation being shown below the section line and the type of ornamentation above the line being identically the same; and Fig. 2 is a side elevation thereof.

I claim:

The ornamental design for a chandelier chain support, as shown.

WILLIAM HORN.

Witness:

ALEXANDER PARK.
